CLAIM

The ornamental design for an optical device reticle, as shown and described.

DESCRIPTION

FIG. 1 is a perspective view of an environment for use with an optical device reticle for an optical device;
FIG. 2 is a view of an embodiment of an optical device reticle for an optical device, as viewed through an eyepiece end of the optical device;

FIG. 3 is a view of the optical device reticle of FIG. 2; and, FIG. 4 is an enlarged view of the optical device reticle of FIG. 2.

In the figures, the dashed lines indicate environmental features that form no part of the claimed invention.
